CLAIM

The ornamental design for a golf ball as shown and described.

DESCRIPTION

FIG. 1 is a perspective view of a golf ball showing our new design;

FIG. 2 is a front elevational view thereof;

FIG. 3 is a side elevational view of the left side thereof;

FIG. 4 is a side elevational view of the right side thereof;

FIG. 5 is a top plan view thereof;

FIG. 6 is a bottom plan view thereof; and,

FIG. 7 is an enlarged fragmentary front elevational view thereof.

The broken lines in the figures depict portions of the golf ball that form no part of the claimed design.

1 Claim, 7 Drawing Sheets
